LIQUID INLET SYSTEM FOR WASHING MACHINES

John Paul Jones and Julius J. Haverstock, South Bend, Ind., and Donald H. Scott, Waltham, Mass., assignors, by mesne assignments, to Avco Manufacturing Corporation, New York, N. Y., a corporation of Delaware

Application November 2, 1949, Serial No. 125,111

12 Claims. (Cl. 68—21)

1

This invention relates to improvements in a vacuum breaker and water inlet system for use in connection with a washing machine of the type in which a flexible bag is collapsed against the laundry to squeeze the liquid and detergent out of the same.

A machine of flexible bag type, on which this invention is particularly adapted for use, is more fully described in copending application Serial No. 5,619, filed January 31, 1948, now Patent No. 2,636,372, dated April 28, 1953, by Henry J. Rand inventor which discloses various automatic features and a cycle of operations suitable for the operation of such a machine.

It is a primary object of the present invention to provide a liquid inlet for a washing machine whereby the flow of liquid in the supply line is limited to a direction into the container of the machine thereby preventing back flow of liquid on a reduction of pressure within said line.

A further object of this invention is to provide a vacuum breaker or so called "air gap" to satisfy various plumbing codes which require an air gap in the liquid line to prevent contaminated liquid from backing up into the line when subjected to a reduction in pressure, while affording a conduit for supplying liquid inside a flexible bag for washing and affording also a means to seal said conduit during extraction or squeeze drying portions of the cycle in such bag.

Another object of the present invention is to provide means for automatically breaking the vacuum in the bag of a suction extraction type of machine after each drying operation during which extraction portion of the cycle the interior of the bag is subjected to a partial vacuum of a very high degree.

A further object of the present invention is to provide means for admitting liquid even under conditions of very low line pressure into the interior of the bag, said means comprising a diaphragm valve providing for liquid flow in one direction only and being adapted to close the liquid inlet line when subjected to a reduction in pressure.

A further object of the present invention is to provide a means of forcing air into the bag along with the inlet water to assure that the bag will return to its normal position after the release of suction or partial vacuum.

Other objects and advantages of the present invention will become apparent from the following more detailed description and illustration in the accompanying drawings forming a part hereof and wherein:

Figure 1 is a central sectional view through a

2

washing machine embodying the essential features of this invention.

Figure 2 is a central sectional view of a combined water inlet-Venturi valve taken along the line 2—2 of Figure 1.

Figures 3 and 4 are central sectional views of a diaphragm valve for admitting liquid into the bag, Figure 3 showing the valve in the open or liquid admitting position, and Figure 4 showing the valve in the closed position, both views taken along the line 3—3 of Figure 1.

Figure 5 is a front elevation of the vacuum release valve and its control mechanism, taken along the line 5—5 of Figure 1.

Figure 6 is a sectional view taken along the line 6—6 of Figure 4 showing the contrasting effective areas of the diaphragm in the liquid admitting valve.

Figures 7 and 8 are sectional views through the pressure relief valve taken along the line 7—7 of Figure 1, Figure 7 showing the valve in closed or bag sealing position, and Figure 8 showing the valve in open or pressure relieving position.

Referring to the drawings, Figure 1 shows a washing machine of the type employing a flexible liquid-and-air-tight bag 10 which is supported within a suitable wrapper 11 and enclosed by a suitable casing or cabinet 12. An agitator 13 is mounted for oscillation centrally of the bag 10 for causing a washing action and is driven by a suitable motor 14 through a transmission mechanism 15.

The bag 10 has an open neck 16 through which the soiled laundry and soap are introduced. A cover 17 is provided for this opening and is adapted to seal said opening on contact with a flexible lip 18 extending from the top of the bag 10. This sealing is necessary to produce an air-tight joint when a suction produces a partial vacuum within the bag 10 thereby to collapse the bag for a squeeze drying operation by means of a suitable pump 19.

In the present machine, liquid is introduced into the bag 10 by means of a suitable thermostatically controlled mixing valve 20 well known in the art and which is attached to suitable hot and cold liquid supply lines. The liquid from the mixing valve 20 passes through a conduit 21, through a Venturi valve 22 to be later described, into a conduit 23, through a diaphragm valve 24 also to be later described, through a conduit 25, and into an opening 26 in the bottom of the bag 10 and communicating with the interior thereof.

When the liquid in the bag 10 reaches a predetermined level, as indicated at "X," a suitable

pressure switch (not shown) is actuated to stop the flow of liquid from the mixing valve 20.

Referring now to Figure 2, the Venturi valve 22 comprises a nozzle member 27 which terminates at 28 in a restricted outlet which increases the velocity of the liquid passing through the valve. The increase in velocity creates a reduction in pressure in an area 29 which causes air to enter the valve through an opening 30 and to be forced into the conduit 23 along with the liquid.

Referring now to Figure 3, the liquid leaving the valve 22 enters the diaphragm valve (thru conduit 23 Figure 1) which comprises a body portion 31, and a flexible circular diaphragm 32 held in place by a cover member 33. The diaphragm 32 is molded in such a manner as to be normally urged to seal the cutoff face or seat 34 of an inlet port 35 in the valve body 31 as shown in Figure 4. The liquid from conduit 23 enters this valve through the inlet port 35 and the pressure thereof urges the diaphragm to assume the position shown in Figure 3 whereupon the liquid is then free to escape through an outlet port 36 in the valve body and enter into the conduit 25 which leads into the bag 10 as aforementioned.

It should be noted that the distance between the diaphragm 32 and the Venturi valve 22 should be great enough, depending upon the diameter of the conduit 23, to furnish a head of water of sufficient pressure to urge the diaphragm 32 away from the seat 34 regardless of the amount of pressure in the inlet line. This arrangement assures that the tub will fill to a normal predetermined level as aforementioned without causing the liquid to rise in the conduit 23 and overflow through an outlet 37 in the Venturi valve 22.

It should also be noted that the Venturi valve 22 must be placed a sufficient distance above the normal water level in the bag to prevent overflowing under normal conditions since there is a natural tendency for the liquid to seek a level in the conduit 23 corresponding to the level in the bag 10.

It has been found through experimentation that since air and liquid both are admitted to the bag, that on stopping of the liquid flow due to actuation of the pressure switch as aforementioned, there is a natural tendency for the air which is trapped in the conduit 23 to rise in the conduit and escape through the outlet 37. In doing this there is also a tendency for a small amount of liquid to regurgitate in the conduit, which necessitates the cuplike container 38 which is designed to hold slightly more liquid than does regurgitate and is made a part of the Venturi valve 22 as shown in Figure 2. After sufficient air has escaped through the outlet 37, the liquid which has risen into the container 38 will again seek its natural level in the conduit 23.

Another important feature of this fill system is the incorporation of a small pressure relief valve 39 in the cover 17 which closes the opening 16 in the bag 10. This relief valve is necessary since the amount of air which is forced into the bag 10 along with the incoming liquid is proportional to the pressure in the inlet line. This relief valve comprises a flexible circular pad 40 which is adapted to cover a series of openings 41 in the cover member 17 and has a spherical button 42 forming a part thereof which is forced into a hole in the cover 17 for attachment thereto. The circular pad 40 is molded in such a manner as to be normally urged to close the openings 41 to

seal the interior of the bag 10 from the atmosphere as shown in Figure 7.

In the event the washing machine is installed in an area having a very high water pressure, there will be an excessive amount of air forced into the bag 10 which normally would collect in the top of the bag and exert a downward pressure on the liquid thereby causing the pressure switch to be actuated too soon and thus create a "false" water level; thus the necessity for this pressure relief valve becomes readily apparent. When such a high pressure occurs, the circular pad 40 will be forced into the position shown in Figure 8, exposing the openings 41 to the atmosphere through holes in the cover member 17, the air taking a path as indicated by the arrows in Figure 8.

After the liquid has reached its pre-determined level as aforementioned, suitable means is provided as aforementioned for causing a washing action to take place in the bag 10 by oscillation of agitator 13. At the conclusion of the washing action, a squeeze drying operation is performed on the laundry in the bag. This action is accomplished by the pump 19 pumping the air and liquid from the interior of the bag 10 thereby creating a substantial vacuum therein (about 26½ inches of mercury in the vicinity of South Bend, Indiana), causing the bag to collapse around the clothes due to atmospheric pressure being exerted on the outside thereof.

It should be noted that the liquid which is in the conduit 25, the diaphragm valve 24, and the majority of the liquid in the conduit 23, will likewise be pumped out.

Referring to Figure 6, which shows a comparison between the vacuum affected area, and the liquid pressure area of the diaphragm 32, it is disclosed that the combination of the bias of the diaphragm 32 toward closing and the slight suction of the pump 19 on the large area of the diaphragm 32 will cooperate to produce a very tight seal between the diaphragm 32 and the seat 34 when the drying operation is being performed on the laundry. It should be noted that the outlet port 36 in the diaphragm valve is sloped downward so that the liquid in the conduits 23 and 25 and the valve 24 will tend to drain by gravity, also the annular space 43 surrounding the diaphragm 32 is capable of being drained by its connection with the outlet port 36 through a small bleed port 44 which permits a majority of the liquid to be drained from the diaphragm valve. This draining of the diaphragm valve is necessary to insure that the diaphragm will return to closed position easily.

At the conclusion of the squeeze drying operation, means is provided for releasing the vacuum in the bag 10 which comprises a vacuum release valve 52, 53 which is operated automatically at the conclusion of each drying period, being actuated by an automatic timer 45, now to be described.

Referring to Figure 5 showing the vacuum release valve 52, 53, there is a cam 46, driven by a shaft 47 of the timer 45 which timer is of the general type more fully described in the patent to Hall, No. 2,313,064 dated March 9, 1943. The cam 46 is an added part for purpose of this invention and has a follower 48 which comprises one free end of a lever 49 pivoted at 50 and biased to ride the face of the cam by the action of a spring 51. Mounted on the opposite free end of the lever 49 is a poppet valve 52 which is adapted to close the flared end of a tube 53 attached to a small

conduit 54 shown in Figure 1 which leads to the opening 26 in the bottom of the bag 10 when the follower 48 rides on one of a plurality of high spots on the cam 46. These high spots correspond to the squeeze dry periods in the cycle of operations described in the aforementioned copending application. At the end of each of the squeeze dry periods the follower 48 is urged into a low spot on the cam 46 due to the bias of the spring 51 which causes the poppet valve 52 to be lifted from the flared end of the tube 53 thereby communicating the interior of the bag 10 with the atmosphere and breaking the vacuum therein.

The operation of the machine is as follows:

The washing operation takes place with the water in the bag 10 at the level indicated at "X" and the clothes inserted through the neck opening 16 with the cover 17 removed and soap added with the clothes. The cover 17 may be in place during the washing operation as the agitator 13 is oscillated.

When the first washing operation has taken place for a predetermined period of time as selected by the operator through timer 45, the pump 19 is started in rotation and draws the liquid and air from the interior of the bag 10 creating a substantial vacuum within the sealed interior of the bag 10 thereby squeezing the clothes between the agitator 13 and the bag 10 in a manner more fully described in co-pending application Serial No. 45,347 filed August 18, 1948, J. P. Jones inventor, now abandoned.

After the clothes are squeezed by the collapsed bag 10, the walls of the bag are, of course closely compacted toward the center of the machine around the agitator 13 and it then becomes necessary to inject rinsing liquid into the bag 10 for a rinsing operation. Furthermore it is necessary that the walls of the bag 10 return to their original position as soon as possible and it would be quite inconvenient if it were required that the cover 17 be removed to accomplish this purpose. It therefore becomes important to admit air along with the liquid coming into the bag 10. Such a result is accomplished by the mechanism herein provided in that when the inlet valve 20 connected to water pressure supply lines admits water under pressure first to the conduit 21, then into the Venturi valve 22. An inspection of Figure 2 will show that the restriction provided increases the velocity of the outlet 28. This increase in velocity causes a reduction in pressure in the region 29 thereby drawing air into the opening 30 and carrying that air with the liquid into the conduit 23. The weight of the liquid in the conduit 23 is sufficient to open the diaphragm 32 to the position of Figure 3 against the vacuum inside the bag which allows an unrestricted flow through the valve 24 into the conduit 25 and into the bottom of the bag 10. The fact that air as well as liquid is admitted, assures a relatively fast return of the walls of the bag 10 to their normal position as shown in Figure 1. The provision of the previously mentioned relief valve 39 in the cover 17 assures that the pressure within the enclosed bag would not exceed a predetermined amount depending upon the pressure at which the relief valve will operate to release air through the openings 41.

With the bag 10 filled again to the predetermined level "X" the agitator 13 is again oscillated to more completely rinse the clothes in the liquid provided.

After the oscillation is continued for a predetermined time, pump 19 is again started in rota-

tion to extract the liquid and air from the interior of the bag 10 to collapse same as in the previous case at the end of the washing operation.

It is to be noted that diaphragm 32 is normally biased to assume the position shown in Figure 4 which is closed position and when the suction of pump 19 acts through the conduit 25 such suction tends to more positively close and seal the diaphragm 32 into the closed position to prevent air from entering the bag 10 through the conduits 23 and 25.

Both at the end of the extraction operation following washing, and at the end of each of the two rinses as shown on cam 46, the vacuum release valve members 52, 53 are caused to separate and thereby cause air to enter through conduit 54 and into the bag 10 as will be evident on inspection of Figures 1 and 5. Conversely, during the time when pump 19 is in operation when liquid and air are being removed from the bag 10 the cam 46 is so shaped to cause the valve members 52, 53 to close and the conduit 54 to be sealed.

Apart from the result accomplished of causing flow of liquid into the container of a washing machine as above described it is an important feature afforded by this invention that the restriction in the supply line produced by the Venturi valve 22 with its chamber 29 producing a reduction in pressure on flow, together with the outlet connection to the atmosphere from the chamber 29 through the outlet 37 which is above the normal level of liquid in the container assures that the flow of liquid in the conduits 23 and 25 is limited to a direction toward the container. Such a construction provides a so-called vacuum breaker feature necessary for satisfying plumbing codes with a minimum of parts. It is apparent from the above disclosure that a reduction in pressure in the conduit 21 will not cause contaminated liquid to "back up" into the supply line but instead such reduction in pressure would simply draw air through the opening 30.

Although one embodiment of this invention is here shown and described it is not intended that it be limited to that particular embodiment or otherwise than by the terms of the appended claims.

We claim:

1. In a washing machine employing a flexible liquid- and air-tight bag having an opening through which laundry may be inserted and having a cover for sealing said opening and means for withdrawing liquid and air from the interior of said bag creating a substantial partial vacuum therein to cause the bag to collapse against the laundry to squeeze out the liquid by pressure on the outside thereof, the combination of a liquid supply line, a conduit in said supply line, a venturi at one end of said conduit forming a restriction in said supply line, said venturi having an opening therein communicating with the atmosphere above the level of liquid in said bag, and a second conduit extending from said venturi and communicating with the interior of said bag at the bottom thereof, whereby the pressure of liquid in said supply line is utilized to force air into said bag with said liquid and a normally closed valve in said cover arranged to maintain a slight pressure and to relieve excessive pressure within said bag.

2. In a washing machine employing a flexible liquid- and air-tight bag having an opening through which laundry may be inserted and having a cover for sealing said opening and means for withdrawing liquid and air from the interior

of said bag creating a substantial partial vacuum therein to cause said bag to collapse against the laundry to squeeze out the liquid by pressure on the outside thereof, the combination of a liquid supply line, a conduit in said supply line, a venturi at one end of said conduit forming a restriction in said supply line, said venturi having an opening therein communicating with the atmosphere above the level of liquid in said bag, a second conduit extending from said venturi and communicating with the interior of said bag at the bottom thereof, a valve in said second conduit normally closed and adapted to be opened by weight of a predetermined volume of liquid therethrough.

3. The combination of claim 2, wherein said second conduit has a liquid capacity equal to said volume whereby to open said normally closed valve regardless of pressure in said supply line.

4. In a washing machine employing a flexible liquid- and air-tight bag having an opening through which laundry may be inserted and having a cover for sealing said opening and means for withdrawing liquid and air from the interior of said bag creating a substantial partial vacuum therein to cause the bag to collapse against the laundry to squeeze out the liquid by pressure on the outside thereof, the combination of a liquid supply line, a conduit in said supply line, a venturi at one end of said conduit forming a restriction in said supply line, said venturi having an opening communicating with the atmosphere above the level of liquid in said bag, and a second conduit extending from below said venturi and communicating with the interior of said bag, whereby the pressure of liquid in said supply line is utilized to force air into said bag with said liquid, said sealing means for said opening in said bag comprising a cover member adapted to seal said opening on creation of a partial vacuum within said bag, said cover member having an opening therein communicating with the atmosphere and a valve in said cover member normally urged to close said opening, said valve being opened by pressure within the bag of predetermined amount.

5. In a washing machine employing a flexible liquid- and air-tight bag having an opening through which laundry may be inserted and having a cover for sealing said opening and means for withdrawing liquid and air from the interior of said bag creating a substantial partial vacuum therein to cause said bag to collapse against the laundry to squeeze out the liquid by pressure on the outside thereof, the combination of a liquid supply line communicating with the interior of said bag, means in said line having communication with the atmosphere for forcing air into said line, valve means in said line operable by pressure of liquid in said line to allow flow of liquid therethrough into said bag, means on said cover for relieving increased pressures within said bag, and means communicating with the interior of said bag at the bottom thereof for equalizing reduced pressures therein.

6. Mechanism as in claim 5, wherein the valve means in said line comprises a resilient member moveable by increase of pressure within said line to allow flow of liquid into said bag.

7. Mechanism as in claim 5, wherein the means for relieving increased pressures within said bag comprises a member moveable to connect the interior of said bag with the atmosphere on increase of pressure within said bag.

8. Mechanism as in claim 5, wherein the means

5 5

for equalizing reduced pressures within said bag comprises a valve operable at fixed points in a cycle of operations to connect the interior of said bag with the atmosphere thereby to release a vacuum therein.

9. In a washing machine employing a flexible liquid- and air-tight bag having an opening through which laundry may be inserted and having a cover for sealing said opening and means 10 for withdrawing liquid and air from the interior of said bag thereby creating a substantial partial vacuum therein to cause the bag to collapse against the laundry to squeeze out the liquid by pressure on the outside thereof, the combination of

15 of a liquid supply line communicating with the interior of said bag, a venturi in said line arranged to force air into said line with said liquid, said venturi being open to the atmosphere at the throat thereof, a normally closed valve in said line below said venturi, said valve being opened responsive to a predetermined volume of liquid, said line below said venturi being of a capacity equal to said volume.

10. In a washing machine employing a flexible liquid- and air-tight bag having an opening through which laundry may be inserted and having a cover for sealing said opening and means 20 for withdrawing liquid and air from the interior of said bag creating a substantial partial vacuum therein to cause the bag to collapse against the laundry to squeeze out the liquid by pressure on the outside thereof, the combination of a liquid supply line communicating with the interior of said bag, a venturi in said line arranged

25 to force air into said line with said liquid, said venturi being opened to the atmosphere at the throat thereof, and a valve in said line biased to closed position, said valve being forced to open position by a predetermined volume of liquid, said line between said venturi and said valve being of a capacity at least equal to said volume, said means for withdrawing liquid and air from the interior of said bag comprising a pump communicating with the interior thereof and with said liquid supply line, whereby a reduction in pressure in said supply line created by said pump causes said valve to seal said line.

11. In a washing machine having cycles of washing, rinsing and squeeze drying, a flexible liquid and air-tight bag having an opening for insertion and removal of clothing, a cover for said opening, means to admit washing fluid to said bag to a predetermined level, said means including an inlet line with an outlet into the bottom of said bag, said line extending outside said bag and above said level, a venturi in said line above said level, said line having a valve between said outlet and the venturi, said valve being responsive to a predetermined volume of liquid, said line above said valve having a capacity equal to said volume, said bag being mounted for expanded and contracted positions, means to create a vacuum within the bag to force said bag to contracted position and thereby to squeeze fluid from the laundry, means to break said vacuum including an outlet from the bottom of the bag to the atmosphere, means to close said outlet during said squeeze drying cycle and to open said outlet after said drying cycle, means to admit liquid to said venturi and said inlet line, said valve admitting liquid after the drying cycle to fill the bag to said level, said venturi admitting air after said drying cycle to said bag to assure prompt return thereof to expanded position.

washing, rinsing and squeeze drying, a flexible liquid and air-tight bag having an opening for insertion and removal of clothing, a cover for said opening, means to admit washing fluid to said bag to a predetermined level, said means including an inlet line with an outlet into the bottom of said bag, said line extending outside said bag and above said level, a venturi in said line above said level, said line having a valve between said outlet and the venturi, said valve being responsive to a predetermined volume of liquid, said line above said valve having a capacity equal to said volume, said bag being mounted for expanded and contracted positions, means to create a vacuum within the bag to force said bag to contracted position and thereby to squeeze fluid from the laundry, means to break said vacuum including an outlet from the bottom of the bag to the atmosphere, means to close said outlet during said squeeze drying cycle and to open said outlet after said drying cycle, means to admit liquid to said venturi and said inlet line, said valve admitting liquid after the drying cycle to fill the bag to said level, said venturi admitting air after said drying cycle to said bag to assure prompt return thereof to expanded position, said cover having a pressure relief valve responsive to a predetermined amount of pressure.
